UNITED STATES PATENT OFFICE

166,811

DEODORANT BLOCK HOLDER

Alfred L. Le Febvre, Windsor, Conn.

Application February 16, 1952, Serial No. 18,549

Term of patent 14 years

(Cl. D16—2)

To all whom it may concern:

Be it known that I, Alfred L. Le Febvre, a citizen of the United States, residing at Windsor, in the county of Hartford and State of Connecticut, have invented a new, original, and ornamental Design for a Deodorant Block Holder, of which the following is a specification, reference being had to the accompanying drawing, forming part thereof.

Fig. 1 is a front view of a deodorant block holder showing my new design, Fig. 2 is a side view thereof, and Fig. 3 is a vertical sectional view thereof taken along the line 3—3 of Fig. 1.

I claim:

The ornamental design for a deodorant block holder, as shown.

ALFRED L. LE FEBVRE.
